UNITED STATES PATENT OFFICE.

CARL EMIL PEDERSEN, OF CHRISTIANIA, NORWAY.

FURNACE.

1,102,292.

Specification of Letters Patent.

Patented July 7, 1914.

Application filed February 21, 1914. Serial No. 820,091.

To all whom it may concern:

Be it known that I, CARL EMIL PEDERSEN, a subject of the King of Norway, residing at Ekebergveien 3, Christiania, Norway, have 5 invented certain new and useful Improvements in Furnaces; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

15 The present invention relates to an arrangement in furnaces for heating nails, blanks of various kinds, etc., the construction of which is intended for quickly heating a large number of blanks in a furnace 20 using little fuel.

In the accompanying drawing is illustrated a constructional form of the furnace which is especially intended for heating nails.

25 Figure 1 is a vertical longitudinal section through the furnace, partially in elevation. Fig. 2 is a plan view of the furnace.

The furnace is operated with compressed air which is supplied to the fire box partly 30 through a pipe, *a*, opening below the grate, *b*, and partly through the top wall of the fire box through the opening *c* through which also the fuel (coal-powder) may be introduced. This blast from above serves 35 *inter alia* to prevent the blast on the underside of the grate from whirling away the fuel from the grate. Thus it serves as it were to balance the blast from below.

Extending upwardly from the base 10 of 40 the furnace is an angular partition wall comprising the substantially vertical branch 11 and the horizontal branch 12. The horizontal branch 12 of the partition wall extends rearwardly in the furnace and stops 45 a considerable distance short of the back wall 13. Depending from the top wall 14 of the furnace is a second angular partition wall comprising a vertical branch 15 and a horizontal branch 16 extending parallel to 50 the horizontal branch 12 of the first mentioned wall. The end of the branch 16 stops short of the vertical branch 11. The horizontal branch 12 is spaced away from the top wall 14 of the furnace and from the 55 horizontal branch wall 16 so that a space, forming a heating chamber, is provided both

above and below the horizontal branch 12, the upper surface of the branch 12 forming a support in one of the chambers for the articles to be heated therein, and the upper 60 surface of the branch 16 forming a support in the other chamber for the articles to be heated therein.

From the fire box, *d*, the flame passes through the flue *e*, which is disposed at the 65 top of the furnace. In this flue is the heating chamber *f* in which the blanks requiring the most intense heating, are introduced through the opening, *g*, in the top of the furnace. Immediately behind the chamber *f* the flue deflects downwardly and returns 70 in a passage, *h*, in the opposite direction. Disposed in this passage is the second heating chamber, *i*, which is intended for blanks not requiring to be heated quite as much as 75 the blanks in the chamber *f*. Immediately behind the chamber *i*, the flue again deflects downwardly to again pass in the opposite direction below the chamber *i*, after which the fire gases are discharged from the furnace through a vertical passage *j*. The flue, 80 as will be seen from the drawing will get the form more or less of a flattened *S*.

An essential condition of the heating effect of the furnace is that the flue should 85 deflect downwardly immediately behind the heating chamber. Thereby the flame and the fire gases, which will otherwise follow the top wall of the passage, will be forced down against the plate *k* or *l*, respectively, 90 on which the blanks are placed so that the same will be heated in a very short time to a high temperature.

The blanks are removed through the lateral openings *m*, *n* which if desired may be 95 provided with doors. Generally, however, these will be superfluous.

The body of the furnace itself is formed in this construction by two stones placed on their edges and each of which constitutes 100 one half of the furnace. The body of the furnace, however, may also be made of a larger number of stones or only of one single stone suitably formed, the whole furnace being generally not made of a larger size than 105 will enable it to be readily moved from one place of operation to another by a couple of attendants which is a matter of great importance in using the furnace as a nail furnace. Of course there is, however, nothing 110 to prevent the same principle to be applied to furnaces with greater dimensions.

I claim:

A furnace having a fire box near one end thereof and a discharge flue near the opposite end thereof, one end wall of said furnace forming one wall of said flue, an angular partition in said furnace having one branch parallel to said furnace end wall to form the opposite wall of said flue, and a second branch forming an article support 10 extending toward but stopping short of said fire box, said second branch being between and spaced away from the base and the top of the furnace, and a second angular partition having one branch forming one wall

of the fire box and a second branch forming 15 an article support extending toward but stopping short of the first mentioned branch of said first mentioned partition, said last named article support being between and spaced away from the top of the furnace 20 and the first mentioned article support.

In testimony that I claim the foregoing as my invention, I have signed my name in presence of two subscribing witnesses.

CARL EMIL PEDERSEN.
